UNITED STATES PATENT OFFICE

GEORGE P. BALL, OF ALLENTOWN, PENNSYLVANIA

COMBINATION PORTABLE LOADER AND CAR UNLOADER

Application filed April 5, 1929. Serial No. 352,724.

This invention relates to an improved combination portable loader and car unloader. One of the objects of my invention is the provision of a device of the above character employing a movable conveyor with means for mounting the conveyor so it may be readily adjusted to various positions relative to the supporting member and be easily positioned with one end in the car to be unloaded, or the device can be so positioned as to readily load a car.

Another object of the invention is the provision of a device of the above character with a vertically adjusted standard carrying a supporting arm for the conveyor which may be moved to various positions relative to the standard so as to adjust the conveyor for various purposes, and also includes means for adjusting the angle of the conveyor in accordance with the work to be carried out.

A still further object of the invention is the provision of a portable device of the above character comprising operating means for the movable parts controlled through suitable clutch mechanism, whereby the various parts may be independently adjusted and retained in various adjusted positions.

Another object of the invention is the provision of a portable loader and unloader of the above character which includes a rotatable supporting arm mounted for vertical adjustment relative to the base of the device, said supporting arm having one end thereof mounted for lateral movement with means for supporting the conveyor at the outer end of the movable part, said movable part being manually adjustable whereby it may be aligned with the main stationary part or moved to a position parallel therewith.

With the above and other objects in view, the invention consists in the novel features of construction, the combination and arrangement of parts hereinafter more fully set forth, pointed out in the claims and shown in the accompanying drawings wherein:

Figure 1 is a side elevation of my improved device, parts thereof being broken away and illustrated in cross section with the conveyor shown in its loading position in

full lines and in its unloading position in dotted lines;

Figure 2 is a top plan view with the conveyor in unloading position;

Figure 3 is a sectional view on the line 3—3 of Figure 2;

Figure 4 is a sectional view on the line 4—4 of Figure 3;

Figure 5 is a detailed top plan view of the upper face of the vertical movable support with parts thereof broken away and illustrated in section;

Figure 6 is a detailed section on the line 6—6 of Figure 3;

Figure 7 is an enlarged view of the outer end of the rotatable support with parts thereof broken away and shown in section;

Figure 8 is a detailed section on the line 8—8 of Figure 7;

Figure 9 is a detailed section on the line 9—9 of Figure 2.

Referring now more particularly to the drawings wherein I have used reference characters to indicate the various parts throughout the description of the machine, it will be noted that the device is supported upon a platform 1 carried by the traction wheels 2. The platform supports the motor 3 and the tubular standard 4, said standard 4 being rigidly fixed to the platform by means of an annular base member 5 preferably angular in cross section as shown in Figure 1.

Slidably mounted within the tubular standard 4 is the adjustable tubular member 6, somewhat smaller in diameter than the member 4 to provide a chamber between the two parts, said parts being maintained in relative spaced relation by means of the spacing rings 7 and 7'. The motor 3 has mounted upon its drive shaft a sprocket 8 connected in any suitable manner to a sprocket 9 on a transverse shaft 10 carried in suitable bearings on platform 1.

Arranged upon the shaft 10 in spaced relation are the two sets of opposed bevel gears 11 and 12, the set 11 co-operating with a bevel gear 13 which has operative connection with the worm gear 14 on a stub shaft 15. Stub shaft 15 carries a drum 16 upon which the cable 17 is wound and unwound.

This cable 17 is used for raising and lowering the tubular standard 6 within the standard 4 and is adapted to pass upwardly over a pulley 18 at one side of the upper end of standard 4, then pass downwardly between the two standards and through a suitable opening in ring 7'. The cable 17 then passes around the two spaced pulleys 19 at the bottom of the inner member 6, thence upwardly through an opening in the ring 7' thence upwardly over a pulley 18', carried by the member 4 directly opposite the pulley 18.

The end of the cable is attached to the upper end of the member 4 as shown at 19'. From this structure, it will be apparent that when the clutch member 20, which controls the connection between the gears 11 and 13 is actuated, the winding drum 16 is rotated in either direction for winding the cable 17 thereon or unwinding it thereover for raising or lowering the member 6.

The bevel gears 12 are adapted to mesh with the gear 21 which has co-operative connection with worm gear 22 driving stub shaft 23 and drum 24. The connection between gears 12 and 21 is controlled by means of the clutch 25.

From this structure, it will be apparent that when it is desired to move the car in close proximity to the platform 1, a cable hitch may be engaged with drum 24 and the drum rotated through actuation of clutch 25 for pulling the car toward the platform.

The upper end of the movable standard 6 is provided with a transverse platform member 26. This platform or table 26 supports spaced bearings 27 and 27'. Rotatable within these bearings is a tubular member 28 having one end closed by means of a plug 29 having an integral bracket 30 supporting one end of a shaft 31, the other end of said shaft being supported by means of a bracket 32 mounted upon the rotatable member 28 and movable therewith.

The end of the rotatable member 28, opposite the plug 29 is closed by means of the interior bearing member 33, it being understood that the plug 29 also forms a bearing for the centrally disposed shaft 34. The shaft 34 extends through the bearing member 33 and has a clutch member 35 upon its outer end. This clutch member 35 co-operates with clutch member 36 of the extension shaft 37 for simultaneously rotating the two parts.

The shaft 37 is centrally disposed within the movable tubular member 28' which has its ends closed by means of the bearing plugs 38 and 38'. The inner ends of the bearing plugs 33 and 38 are provided with interfitting parts so that when they are disposed in alignment, as shown in Figure 3, these parts, which comprise the reduced sleeve 39 and the tapered socket 39' will prevent lateral movement of the rotatable members 28 and 28'.

Extending laterally from the bearing plug

33 are the brackets 40 formed with bearing parts 41 and extending through these bearing parts is a shaft 42 which also extends through the bearing member 43 on the plug bearing 38, the bearing 43 being disposed between bearing members 41 as shown in Figure 1 and rotatable with shaft 42.

The outer end of shaft 42 carries a worm gear 44, meshing with worm 45 on shaft 46. This shaft 46 carries a hand crank 47 whereby to manually impart movement to shaft 42 for adjusting the movable part 28' relative to the main part 28.

The outer end of shaft 37 is provided with spaced collars 48 and 48' and movable between these collars is a locking arm 49 which is adapted to move shaft 37 toward shaft 34 in order to engage the clutch members 35 and 36, but when the arm 49 is withdrawn from between the collars, the clutch members 35 and 36 may then be disengaged for shifting the part 28'.

It will be apparent from the foregoing that the sectional part 28' of the rotatable tubular member can be either positioned in alignment with the member 28, as shown in full lines in Figure 2, or may be quickly and easily positioned parallel with member 28, as shown by the dotted lines in Figure 2. When the member 28' is moved to the dotted line position shown in Figure 2 so that it lies parallel with member 28, it is necessary to provide some sort of rigid support for the member and this support comprises an arm 50 having a clamping part 51 to embrace the section 28', while the inner end of the arm is supported upon the section 28 or is stationary relative to this section.

The inner end of the arm is provided with a sleeve 52 embracing member 28 and disposed between bracket 32 and bearing 27'. From this, it will be apparent that when the member 28' is moved to a position parallel with member 28, it will be securely held in this position through the clamp member 51 on arm 50.

The section 28' adjustably supports the conveyor 53, through the medium of the collars 54, embracing member 28' and movable therewith. The conveyor 53 may be any conventional type including loading buckets 54 operated through the sprocket and chain connections and has at its upper end an angularly disposed chute 55 whereby the material carried upwardly by buckets 54 will be deposited in the chute and carried off to the desired location.

In order to impart movement to the several parts described, the driving connection to the motor 3 will now be set forth. Mounted upon shaft 10 is a sprocket 56 operatively connected to sprocket 57 on stub shaft 58 mounted in suitable bearings 59. This sprocket 57 is loosely mounted on stub shaft 58 but is operatively connected with the shaft by

means of a manually operated clutch 60. When the clutch 60 is engaged with the hub of the sprocket 57 it imparts movement to a second sprocket 61 which is operatively connected with the sprocket 62 which rotates shaft 63 by means of a sprocket chain passing over sprocket 62, sprocket 64 and sprocket 65, the latter on shaft 63. Sprocket 62 is rotatably mounted upon the stationary tubular member 4 while sprocket 64 is carried by the movable ring 66 which is connected by means of rod 67 to the upper end of the movable tube 6.

In order to prevent movement on the part 15 of the ring 66 relative to member 4, the ring 66 is provided with guide grooves, receiving the guides 68.

From this, it will be apparent that regardless of the position of the member 6 relative 20 to the member 4, operative connection between shafts 58 and 63 is established.

Upon the outer end of shaft 63 is a sprocket 69 operatively connected with sprocket 70 upon the end of shaft 34 which imparts movement to shaft 34 and extension part 37. Shaft 34 also supports a sprocket 71 operatively connected with sprocket 72 upon the outer end of shaft 31, thus imparting movement to shaft 31.

When it is desired to rotate the tubular parts 28 and 28', it will be noted that part 28 is connected to shaft 63 through the operation of a clutch 73 disposed between bevel gears 74 which co-operates with bevel gear 75 on stub shaft 76. The stub shaft 76 carries a sprocket 77 operatively connected with sprocket 78 which operates a worm 79 meshing with the worm gear 80 on member 28. From this, it will be apparent that through 40 the medium of the clutch 73 rotative movement may be imparted to members 28 and 28'. It will be apparent that the opposed bevel gears 74 are loosely mounted on shaft 63 and are only rotated through their connection 45 with clutch 73.

It will be apparent from the foregoing, that upon the rotation of shaft 34 and part 37, the sprocket 81 upon the outer end of part 37 will be actuated and as it has operative connection with sprocket 82 on conveyor shaft 83, movement will be readily imparted to the conveyor.

The shaft 83 supports the spaced sprockets 84 operatively connected to similar sprockets 85 on shaft 86 thus imparting movement to the buckets 54.

On the outer end of the extension part 37, there is mounted a second sprocket 87 spaced from sprocket 81 and adapted to be operatively connected with sprocket 87' on shaft 31 when the member 28' is moved to a position parallel with member 28 as shown by dotted lines in Figure 2, so that operative connection to the conveyor may be established regardless of the position of the member 28'.

While I have shown and described the preferred embodiment of my invention, it will be apparent that slight changes may be made in the construction when putting the invention into practice without departing from the spirit of the same or the scope of the appended claims.

I claim:

1. In a device of the class described, a portable platform, a vertically adjustable standard carried thereby, a rotatable member at the upper end of the standard, an extension at one end of the rotatable member adapted to be aligned therewith, a conveyor at the outer end of the extension, means for moving said extension to a position parallel with the rotatable member and means for imparting movement to the conveyor when the extension is in either position.

2. A device of the class described including a portable platform, a vertically adjustable standard carried thereby, a rotatable member at the upper end of the standard, an extension aligned with the rotatable member, a shaft extending through the rotatable member and the extension, a conveyor carried by the extension, means forming operative connection between the shaft and the conveyor for imparting movement to the same, means for moving the extension to a position parallel with the rotatable member.

3. In a device of the class described, a portable platform, a vertically adjustable standard carried thereby, a rotatable member at the upper end of the standard, an extension for the rotatable member, a shaft through the rotatable member and extension, a clutch connecting the shaft part in the rotatable member with the shaft part in the extension, a conveyor carried by the extension, means connecting the shaft with the conveyor for imparting movement to the same, means for moving the extension from a position aligning with the rotatable member to a position parallel therewith and means for operating the conveyor in the latter position.

4. In a device of the class described, a portable platform, a vertically adjustable standard carried thereby, a rotatable member at the upper end of the standard, an extension to be aligned with the rotatable member, means for mounting said extension to permit the same to be swung to a position parallel with the rotatable member, a conveyor at the outer end of the extension, means for imparting movement to the conveyor when the extension is in either position and means for swinging said extension from one position to the other.

5. In a device of the class described, a portable platform, a stationary tubular standard carried thereby, a movable tubular member slidably mounted in the standard, means for retaining said movable member against rotation relative to the standard, means for rais-

ing and lowering the movable member within the standard, a rotatable and laterally swinging support at the upper end of the movable member and a movable conveyor carried by said support.

6. In a device of the class described, a portable platform, a vertically adjustable standard carried thereby, a rotatable member at the upper end of the standard, an extension 10 adapted to be aligned with the rotatable member, manually operated means for moving said extension from alignment with the rotatable member to a position parallel therewith, a conveyor carried by the extension 15 and means for imparting movement to the conveyor.

7. In a device of the class described, a platform, a vertically adjustable standard carried thereby, a rotatable member at the upper 20 end of the standard, an extension adapted to be aligned with the rotatable member, means for moving said extension from alignment with the rotatable member to a position parallel therewith, a conveyor carried by the extension 25 and means for imparting movement to the conveyor.

8. A device of the class described including a portable platform, a vertically disposed standard carried thereby, a rotatable member 30 at the upper end of the standard, an extension adapted to be aligned with the rotatable member, means for moving the extension to a position parallel with the rotatable member, a conveyor carried by the extension, and 35 means for imparting movement to the conveyor.

9. A device of the class described, including a portable platform, an adjustable standard carried thereby, a rotatable member supported by the standard, an extension to be 40 aligned with the rotatable member, manually controlled means for moving said extension to a position parallel with the rotatable member, a conveyor carried by the extension, and 45 means for imparting movement to the conveyor when the extension is in either position.

In testimony that I claim the foregoing I have hereunto set my hand at Allentown, in the county of Lehigh and State of Pennsylvania.

GEORGE P. BALL.
